UNITED STATES PATENT OFFICE

WALTER R. STEIN, OF BRAINERD, MINNESOTA

NOZZLE HOLDER

Application filed April 6, 1929. Serial No. 353,082.

My invention relates to a new and useful improvement in nozzle holders, wherein it is desired to provide a holder for nozzles such as a nozzle for a fire hose to keep the nozzle 5 rigidly and securely in place when it is not being used.

My holder is particularly adapted for use upon the running boards of fire trucks, to hold the nozzles securely while the trucks are 10 answering the alarms or at any time when the nozzles are not in use. My construction is such that the nozzles are held with sufficient strength to keep them from working loose and falling from the truck even when 15 the trucks are traveling over the roughest of roads, thus doing away with the possibility of losing the nozzles, or causing delay by having one of them fall from the truck.

It is a feature of my invention that the 20 nozzles held in my device, being held very securely may be placed upon the running board or some other easily accessible portion of the truck. By using my device, it would be no longer necessary to strap the nozzles 25 down, or to put them in some portion of the truck where they are not likely to fall out, but where they are hard to get at for instant use in case of necessity.

It is an added feature of my holder that 30 it may be simply and quickly operated to release the nozzle placed upon it when it is to be taken off. The construction is such that a slight pressure upon a foot lever conveniently placed projecting from one side of 35 the base of my holder will free the nozzle so that it may be lifted clear of the holder and connected to the hose. Thus it may be seen that by the use of my invention much time may be saved in preparing the hose for fighting 40 a fire, a very important fact in view of the fact that a few seconds mean a great loss when a large fire is under way.

It is my purpose to form my nozzle holder in an attractive manner to conform with 45 the rest of the furnishings and equipment of the fire trucks, and to enable it to be used in a position where it will be exposed to view without detracting from the attractive appearance which the trucks of this style 50 present.

Other features and objects as well as the specific construction in detail will be more clearly brought out in the following specification and claims.

In the drawings forming a part of this 55 specification:

Figure 1 is a perspective view of my nozzle holder.

Figure 2 is a side view of the same.

Figure 3 is a bottom view of the base of my 60 nozzle holder.

My nozzle holder A is constructed of a design intended to overcome any tendency on the part of the nozzle to become accidentally disengaged. My holder A is formed of a 65 base portion B, engaging shoulder portions C and an operating mechanism D which is adapted to operate the engaging shoulder portions C in such a manner as to allow easy attachment and detachment of the nozzle to 70 be held.

The base portion B is formed of a flat plate-like member 10 which is formed with integral legs 11 of a very substantial nature adapted to space the plate 10 away from the surface 75 of the running board or platform upon which the holder is mounted. This spacing allows the surface beneath the base B to be cleaned, allows the plate to be more securely attached than would be the case if the entire lower 80 surface of the plate fitted against the surface to which it is to be attached, and permits a portion of the operating mechanism D to extend slightly downward from the plate 10. A number of holes 12 are formed in the base, 85 and these holes are countersunk in order that the heads of the screws or bolts used to fasten the nozzle holder to the attaching surface will not extend upward from the upper surface of the plate 10 to catch clothing and 90 will not detract from the appearance of the holder.

Upon the upper surface of the plate 10, I 95 construct a pair of engaging shoulders C. These engaging shoulders are formed with a base portion 13, the lower surface 14 of which rests on the upper surface of the plate 10, and which extends upward from the lower surface to an inwardly extending integral flange portion 15 which is adapted to act as 100

a rest for the edge of the nozzle held within my holder. From this inwardly extending flange portion 15, the shoulders C extend upwardly to form a nozzle engaging portions 16. These shoulders C are rounded and are of a shape to best fit a certain size nozzle, although a small variation would not be influential in causing my holder to lose its gripping power. The design is such that the 10 shoulders C are adapted to form segments of a circle the size of the inside of the nozzle when the nozzle is being held. The upper engaging portion 16 of the shoulders are formed with threads 17 of the correct size to correspond with and engage the internal threaded portion forming the end of the nozzle. Thus, when the nozzle is being held in my holder, I have virtually the same firmness and rigidity as would be the case if the nozzle were 15 20 screwed down upon a threaded plug fastened to the running board of the truck.

Thus, in effect the shoulders are of the same formation as would be the case if I constructed a short section of heavy pipe with a flange 25 portion extending inwardly at one end, and a short threaded section of heavy pipe of a smaller diameter attached to the inwardly extending flange portion, and then cut a portion out of the pipe lengthwise to the pipe 30 to leave two separate segments or shoulders.

At the center of each of these segments or shoulders C, I form an inwardly extending lug 18 which is held by the bolt 19 to the inner wall of the engaging portion of the 35 shoulders. One segment 20 of the shoulders C is firmly fastened to the base plate 10 by the bolts 22. The other segment 23 is mounted slidably upon the base plate 10. A sturdy coil spring 24 is adapted to fit over the lugs 18 40 and is adapted to hold the two shoulders as far apart as is possible, the motion of which is restricted by the operating mechanism D.

The operating mechanism D allows the segment 23 to be moved along the upper surface 45 of the plate 10 to come nearer to or farther from the other segment 20. Part of the lower surface 14 of one shoulder or segment 23 is mortised or cut away at 26 to allow a strip 27 to fit in the cut away portion 26 and be 50 secured firmly to the segment 23 by suitable bolts or other means. This strip, preferably formed of the same material as the rest of the holder, extends along the upper surface of the plate 10, through an aperture formed in 55 the center of the lower portion 13 of the stationary segment 20, and merges into a bifurcated end section 28 between the shoulders 29 on which a lever 30 is adapted to pivot. This lever 30 is equipped with an enlarged and 60 flattened portion 31 at one extremity, and is suitably curved at its other end 33 to engage the edge 34 of the plate 10. In order that the lower surface 14 be held tightly against the plate 10 at all times, a slot 35 is formed 65 in the plate and a washer 36 is then connected

to the strip 27 by the bolt 37 extending through the slot 35. This washer holds the strip 27 down against the upper surface of the plate 10, and is just sufficiently loose to allow the segment 23 to be moved freely when 70 desired.

In operation, when it is desired that a nozzle be placed upon my holder, it is only necessary to press downward with the foot upon the enlarged portion 31 of the lever 30, which 75 serves to force the end 33 against its fulcrum, the edge 34 of the plate 10, and to move the strip 27 against the tension of the spring 24 to allow the segment 23 to come closer to the other segment 20. The nozzle 80 may now be placed upon the holder. The pressure of the foot may then be released and the spring 24 causes the shoulders C to spread apart, or allows the segment 23 to move away from the segment 20. The threads 17 then 85 engage with the threads upon the inside of the nozzle, and the nozzle is locked securely in place.

The operation for removing the nozzle is identically the same as has been described. 90 The lever 30 is forced downwardly by the pressure of the foot, the jaws are brought nearer together, and the nozzle may then be easily taken off.

I have thus provided a nozzle holder which 95 is very simple in operation, very easily and economically constructed, and which is installed in a short space of time. I have found my holder to be practical, and an aid in saving valuable time when detaching and attaching 100 the nozzle. Furthermore, the simplicity of construction marks it as being a device of high merit which may be obtained at little expense.

In accordance with the patent statutes, I 105 have described the principles of operation and novel features of my nozzle holder, and while I have endeavored to present the best embodiment thereof, I desire to have it understood that the same is only illustrative of a 110 means of carrying out my invention, and that the same may be changed within the scope of the following claims without departing from the spirit of the invention.

I claim:

1. A holder for a fire hose nozzle including, 115 a base adapted to be rigidly supported to a fire truck, a rigidly secured collar section having nozzle engaging threads formed thereon, a movable collar section having nozzle engaging threads thereon, spring means for holding said collar sections spread apart, and means for operating said movable section towards said first section to release the nozzle supported thereby.

2. A support for a fire hose nozzle comprising, collar sections having threads for engaging the nozzle formed thereon, means for holding said sections spread apart against said nozzle, and means for moving said en- 120 125 130

gaging sections together in a manner to release the fire hose nozzle virtually instantly from said holder.

3. A support for a hose nozzle for fire trucks having a base member adapted to be rigidly attached to the truck, threaded collar sections adapted to engage the threaded portion of the hose nozzle, means for holding said sections spread apart to engage the nozzle under tension to rigidly support the same to a fire truck, and means for releasing said threaded sections from the nozzle to quickly release the same.

4. A hose nozzle support including, sections having threads formed thereon for engaging with the threaded portion of the nozzle, spring means for spreading said sections apart to cause the same to grip the nozzle under spring tension to rigidly support the same, and lever means adapted to operate said sections to release the nozzle, the threaded portions of said sections permitting the tightening of the nozzle by a threading action in attaching the same to said holder.

25 5. A nozzle support and release including threaded means adapted to be spread apart to engage the threaded portion of the nozzle, and means for quickly releasing said threaded means from said nozzle by a non-threading

30 35 action.

6. A nozzle support comprising, expandible sections, spring means for holding said sections expanded, means for contracting said sections, said sections being adapted to rigidly support a nozzle when expanded and instantly release the same when contracted.

7. A nozzle support comprising, a base member adapted to be rigidly attached to a support, collar sections, some of which are rigidly attached to said base and others movable, spring means for holding said sections expanded, and lever means for contracting said sections to provide a quick release for a fire nozzle.
